UNITED STATES PATENT OFFICE.

ERVIN A. LEWIS, OF MOUNT VERNON, NEW YORK.

WINDOW.

No. 908,471.

Specification of Letters Patent.

Patented Jan. 5, 1909.

Application filed May 10, 1907. Serial No. 372,888.

To all whom it may concern:

Be it known that I, ERVIN A. LEWIS, a citizen of the United States, and a resident of Mount Vernon, in the county of West-
5 chester and State of New York, have invented a new and Improved Window, of which the following is a full, clear, and exact description.

This invention relates to improvements in
10 windows, the purpose of which is to pro-
vide a construction involving the usual slid-
ing sash, the latter being adapted to be also
swung from the window opening preferably
to the inside of the room, whereby the pas-
15 sage of the air through the window opening
is altogether unobstructed.

The invention further resides in certain
20 special features of construction and ar-
rangement of parts which will be fully set
forth hereinafter and particularly pointed
out in the claims.

Reference is to be had to the accompany-
25 ing drawings forming a part of this speci-
fication, in which similar characters of ref-
erence indicate corresponding parts in all
the figures.

Figure 1 is a perspective view of a win-
30 dow embodying my invention showing the
sash thereof swung slightly from the win-
dow frame; Fig. 2 is a vertical section
through one of said sashes at the point of
connection with the window jamb; Fig. 3 is
35 a view of a sash cord holding device form-
ing an element of the construction; Fig. 4
is a cross section on the line 4—4 of Fig. 5;
Fig. 5 is an inverted plan view of one mem-
ber of one of the bottom hinges; Fig. 6 is a
40 perspective view of one member of one of
the top hinges; Fig. 7 is a perspective view
of a member of the bottom hinges, and Fig.
8 is a plan of one member of one of the top
hinges.

A window frame 10 of the usual or other
45 preferred construction carries the usual slid-
ing sashes 11 and 12 which are counterbal-
anced at both sides by counterweights at-
tached to cords 13. Near the center of the
frame 10 the parting bead, as also the inside
50 bead, are cut through as indicated at 14, the
lower portion of the former being bodily
displaceable and the latter being hinged at
15 to the window-jamb to swing to the inside
of the frame. At the opposite side of the
window frame, preferably a slight distance
55 above the window sill, a hinge member as
shown in Fig. 5, comprising a casing 16

slidably receiving a slide 17, is let into the
jamb as illustrated in Fig. 2, one hinge
member being provided for each sash. The
outer end of the casing 16 is constructed 60
with a flange 18 which is provided with
suitable screw-holes for securing the casing
in place. The slide 17 is constructed with a
central slot 19 having an enlarged portion
20 adjacent to a flange 21 formed at its ex- 65
tremity. This slot 19 receives a pin 22 pass-
ing through the casing 16, which limits the
extent to which the slide may be withdrawn.

Hinge members of approximately the
same construction are let into the window- 70
jamb a distance above those just described
slightly greater than the length of the
sash as shown in Fig. 8, each comprising a
casing 16^a having a flange 18^a, the casing
being essentially the same as the casing 16 75
and slidably receiving a slide 17^a constructed
with a central slot 19^a. This slot, however,
differs from the slot 19 of the slide 17 in that
it is extended to the flange 21^a only and is of
uniform width throughout. 80

The hinge members which coöperate with
the upper hinge members carried by the
jambs as shown in Fig. 8, and provide a
swinging connection for the sash, each con-
sists of a corner plate 23 shown in Fig. 6, 85
having screw openings for attaching it to
the corner of the sash and shaped to receive
and confine on its under face when applied
in position, the angular end of a hook 24, the
latter projecting slightly above the plate 23 90
and curved in the direction of the opposite
side of the sash as clearly shown.

The hinge members which are carried at
the bottom of the sash, each coacting with a
hinge member as shown in Fig. 5, com- 95
prise a plate 25 having a tongue 26 cut from
one corner and downwardly-turned as shown
in Fig. 7, the plate 25 being provided with
a screw hole or other attaching means for
fastening it to the under edge of the sash, as 100
shown in Figs. 1 and 2. By this construc-
tion when it is desired to swing either or
both sashes from the window opening, they
are lowered until they pass below the slides
17^a which are thereafter drawn from their 105
respective casings 16^a. By now raising the
sash, the hooks 24 will pass through the slots
19^a until the plates 23 contact with the bot-
tom of the slides. The slides 17 should then
be drawn outwardly at the bottom of the 110
sash until the tongues 26 register with the
enlargements 20. By now swinging the

lower portion of the inside bead to one side on the hinges 15, the inner sash may be swung horizontally on the hinges from the window frame; also by removing the lower 5 portion of the parting bead, the outer sash may be likewise swung. The sash cords should, however, be disconnected from the window and secured at some convenient point until again ready to place the sash in 10 sliding operation. For this purpose I have shown a device in Figs. 1 and 3, consisting of a notched arm 27 pivotally connected to a plate 28, the latter being flanged at opposite ends and secured to the frame in the manner 15 shown in Fig. 1. By this construction after the sash cords are disconnected from the sash and engaged with the notches on the arm 27, the knots in the ends of the cords will prevent them from slipping through, 20 and the arm will be retained in a substantially horizontal position by the upper flange on the plate 28.

It will be apparent to those skilled in the art to which this invention appertains, that 25 numerous changes in the construction from that hereinbefore described and shown in the accompanying drawings may be resorted to within the scope of the annexed claims.

Having thus described my invention I

claim as new and desire to secure by Letters 30 Patent:

1. In a window, the combination of a frame, a sash slidable in the frame, casings fixed within the frame, slotted slides in the casings movable into and out of the path of 35 the sash, with the slot in the bottom slide extended through its outer end, and means projecting from the top and bottom edges of the sash adapted to respectively pass through the slot of the top slide and engage thereover, and enter the slot of the bottom slide when the latter is drawn outwardly.

2. In a window, the combination of a frame, a sash slidable in the frame, slides carried by the frame movable into the path of 45 the sash, and devices carried by the top and bottom of the sash, one of which is adapted to engage with one of the slides when the sash is moved vertically, and the other device engaging with the other slide by drawing 50 the slide outwardly.

In testimony whereof I have signed my name to this specification in the presence of two subscribing witnesses.

ERVIN A. LEWIS.
